UNITED STATES PATENT OFFICE.

HERMANN NONNAST AND WILHELM TESAR, OF CHICAGO, ILLINOIS.

EXTENSIBLE TABLE.

1,333,035.

Specification of Letters Patent.

Patented Mar. 9, 1920.

Application filed May 10, 1915, Serial No. 27,038. Renewed August 9, 1919. Serial No. 316,493.

To all whom it may concern:

Be it known that we, HERMANN NONNAST and WILHELM TESAR, citizens of the United States of America, and residents of Chicago, Cook county, Illinois, have invented a certain new and useful Improvement in Extensible Tables, of which the following is a specification.

Our invention relates to improvements in extension tables and one of the objects of our invention is to provide an improved extension table which will be simple, durable and reliable, in construction and effective and efficient in operation.

15 Other objects of our invention will appear hereinafter.

Our invention consists in the features of novelty exemplified in the construction, combination and arrangement of parts herein-
20 after described, shown in the accompanying drawings and more particularly set forth in the appended claims.

Referring to the accompanying drawings:

25 Fig. 1 is a bottom plan view of an extension table in non-extended position, embodying our invention, the legs being removed and the leg-supporting bridges being partly broken away to show other operating parts;

Fig. 2 is a longitudinal sectional view substantially on the line 2—2 of Fig. 1;

Fig. 3 is a transverse sectional view substantially on the line 3—3 of Fig. 1;

30 Fig. 4 is a somewhat enlarged sectional view on the line 4—4 of Fig. 1, showing the structure associated with one end of the table for extending that end. This view shows the end wing of the table partially pulled out and with the extension leaf and its parts almost ready to rise in position;

40 Fig. 5 is a view similar to Fig. 4 except that the end wing has been further extended and the extension leaf is about ready to rise into the plane at the top of the table.

Fig. 6 is a view similar to Figs. 4 and 5 except that the leaf has been operated and has risen into the plane of the top of the table;

50 Fig. 7 is a view similar to Figs. 4, 5 and 6, but showing the extension leaf completely in position;

Fig. 8 is a detail sectional view substantially on the line 8—8 of Fig. 1;

55 Fig. 9 is a detail perspective view of the underside of the table showing the operating

mechanism in connection with one of the extension leaves.

The structure shown in the drawings has a central body portion A which is substantially rectangular in top plan, and two movable or extensible end wings B at opposite ends of the body portion and which are preferably semi-circular in plan, as clearly shown in Fig. 1. The body portion comprises a flat top board 1 of proper dimensions, and two side aprons or depending flanges 2. In this particular structure the table is provided with four legs or supports 3 which are positioned at the four corners of the body section A although obviously the position or character of the supporting members may be of that type for the particular circumstances. For this reason the body section has two bridge members 4 at its ends to which the legs 3 are attached. These bridges are fastened at their ends to the lower edges of the side aprons 2, as clearly shown. This arrangement forms a rigid, substantial yet comparatively light weight structure and provides the proper space beneath the top board 1 for the extension leaves or sections and other operating parts. Along the under edges of the top board 1 are angle irons 6 one of the flanges of which are fastened to and support the top board 1 while the other flange is attached to the side aprons. These angle irons reinforce the structure, render it rigid and strong, hold the parts permanently in their proper relation and thus entirely eliminate warping of the body section. By thus reinforcing the body section 1 the other operating parts of the structure can be maintained in proper relation. The upper or horizontal flanges of these angle reinforcing members are secured to the under surface of the top board. This leaves a clear, unobstructed space or guideway for the extension leaves and permits them to lie close up under the top board and lessens the height to which they must be elevated to bring them into position. The end sections or wings B have top boards 10 and curved aprons or flanges 11 which, when the table is closed, form a continuation of the side aprons 2. The top boards 10 lie in the plane of the main top board 1 whether the end wings are in open or closed position and these wings or end sections are mounted to move longitudinally of the table toward and from the body section. The end sections are

mounted on the outer ends of slides, being fastened to the under sides of the top boards 10, so that these slides serve as supports for the end sections and at the same time permit said end sections to be moved longitudinally. They have a tongue and groove connection 14 with a fixed slide member 15 which is common to and positioned between the corresponding slides 12 and 13 of both sets thereof. For convenience the fixed members are fastened to the bridge members 4. The slides 12 and 13 are preferably as long as the intermediate or fixed members 15 so that they will have a comparatively long bearing on said fixed member even when the table is fully extended. The slides are prevented from separating from the fixed members 15 by bridge straps 16^a which as shown span or embrace the three members 12, 13 and 15 of each group and which are fastened to the fixed members 15. This construction is preferable to the more expensive dove-tail connection usual in extension tables and facilitates assembling of the parts. The particular structure shown in the drawings has two extension or extra leaves or sections C which normally occupy positions in the same plane beneath the main section top board 1, but when the end sections or wings B are pulled out, the leaves C are adapted to be automatically raised or elevated into the plane of the top boards 1 and 10 and interposed between said boards. One of the leaves is associated with space provided at each end of the body section when the end section is pulled out. Each leaf is supported by a pair of cleats 16 and 17 transversely disposed across its underside. These cleats are connected with the slides 12 and 13 by the links 18 and 19. These links are pivotally connected to the cleats and to the slides so that they form parallel motion connections which permit the leaves C to be swung bodily in an arc toward the corresponding end section B, although maintaining the leaf horizontal or parallel with the top boards 1 and 10. The inner links 18 are extended downwardly below the slides 12 and 13 and are adapted to strike or engage stops 20 which, upon the continued pulling of the slides outwardly, causes the links 18 to swing about their pivots 21 and throw or raise the leaves into the plane of the top boards 1 and 10, as shown in Figs. 4, 5, 6, and 7. This occurs after the slides 12 and 13 have carried the leaves outward in their original plane to the position in the open spaces between the top boards 1 and 10. These spaces are wider than the width of the leaves so as to provide room for the leaves to travel upwardly and clear the end edges of the top board b. The parts are so proportioned that when the leaves have risen to their proper height their edges will abut the edges 22 of the top

boards 10 and the leaves will thereby be prevented from moving beyond their proper position. After the automatic positioning of the leaves in this manner when the end section B is pulled outwardly, the end sections B are pushed inwardly, carrying the slides and leaves until the leaves are clamped between the edges of said top boards 1 and 10, the space between said top boards being thus shortened to the width of the leaves. The edges of the top boards 1 and 10 and the leaves C may be provided with dowel pins 23 and corresponding sockets to lock the leaves in position against relative displacement as clearly shown. When the leaves are thus positioned the links or levers 18 and 19 stand substantially vertical and take the weight of the leaves and the boards to which said leaves may be subjected. When the extension leaves are to be returned and the table collapsed or the table shortened in length, the end sections B are pulled outwardly until sufficient space is provided in which the leaves may again be swung downwardly into their original plane, after which the end sections B are again pushed inwardly until their edges 12', abut and interlock with the edges of the top board 1. This carries the leaves and slides to their normal position beneath the main section of the table. In order that the depending ends of the lever links 18 may pass the bridge members 4 in both directions of movement the bridge members are provided with grooves 24 which register with the paths of movement of said links. It will be noted that the projecting ends of the lever links 18, which are adapted to strike the stops 20, are peculiarly curved so that after they strike the stops and operate to swing the leaves into substantially the position shown in Fig. 6, they swing about their pivots 21 to such an extent that they can pass over and beyond the stops 20. In other words, they are so proportioned that they act against the stops 20 until the extension leaf is almost in the position as shown in Fig. 6, and then they clear the stops 20 and their operating ends are carried past the stops 20. The momentum which is imparted to the leaves while they are rising is sufficient to carry the leaves into abutting position with the edges 12' of the end sections B during the period when the ends of the lever links 18 leave the stops 20 to pass over and beyond them. The results of these operations, therefore, position the lever links beyond the stops 20. This action occurs during the opening or extending operation of the table. Assume now that the parts are in the extended position shown in Fig. 7, and that the table is to be shortened or reduced in length. As before mentioned, this is done by pulling out the end section B until a sufficient space is provided in which

the leaf may swing downwardly into its lower position. The parts will be in the position shown in Fig. 6. Having extended parts to this position, the extension leaf is then swung inwardly and downwardly about the pivots 21 of the links 18 and 19. This, of course, swings the lever links 18 about said pivots and positions their operating or projecting ends below the plane of the stops 20. But since these projecting ends are now on the outer side of the stops 20, it is necessary that the stops 20 be movable in order to permit the ends of the lever links 18 to pass when the end section is pushed inwardly to close the table. For this reason we, therefore, make these stops 20 in the form of levers (see Fig. 1), which are pivoted at 30 in suitable slots or depressions in the underside of the fixed slide members 15. These levers and the slots in which they are positioned, as shown clearly in Fig. 1, are so formed that the stop ends 20 will swing inwardly to permit the projecting ends of the lever links 18 to pass during the closing movement of the parts, but to hold the stops rigid in position when the table is being extended. During the closing movement of the table, the stops 20 will, therefore, be swung out of the way to permit the lever links 18 to pass, and they will remain so until restored to a dropping position ready for the next operation of extending the table. In order, therefore, that these stop levers may be restored to operative position, I provide them with ends or arms 31 projecting on the opposite side of the fixed members 15. These restoring ends 31 are adapted to be struck or engaged by projections 32 fastened to the aprons 11 of the end sections B. They are preferably in the form of metal strips having their ends, as shown clearly in Fig. 1, so arranged that they will strike the ends 31 of the stop levers, just as the edges of the top boards 1 and 10 come together in the act of closing the table. These restoring members 32, therefore, swing the top ends 20 again outwardly into position to engage the lever links 18 when the table is again extended. As previously explained, the end sections B must be pulled outwardly until there is sufficient space between their edges 12 and the edges of the main table board 1 to permit the extension leaves to rise in arcuate paths of the plane of the table top. It will readily be seen, therefore, that if the extension leaves were fixed to the transverse cleats 16 and 17 there would be a fixed space between the outer edges of the extension leaves and the edges 12 of the end sections. Hence when the table is reduced in length and the leaves positioned beneath the main top board 1, the leaves would have to be moved inwardly from the edges of the top board a distance corresponding to the distance between the edges of the leaves and the edges 12 of the end sections. The space, therefore, between the outer edges of the leaves and the edges of the main top board 1 would be wasted so far as the width of the leaves are concerned, and in order to obtain a maximum width of leaf and to thereby utilize this waste space, we provide a lost-motion connection between the leaves and the transverse cleats 16 and 17. We obtain this lost-motion connection by providing guide-ways in which the cleats 16 and 17 may have a sliding movement. These guide-ways in the present structure are preferably in the form of transverse cleats 35 which are L-shaped in section and which are permanently fastened by screws 36 to the underside of the leaves and which confine the cleats 16 and 17 between themselves and the corresponding slide members 12 and 13, respectively. Since these cleats 16 and 17 have a sliding movement in their guide cleats 35, and are connected to the slide members 12 and 13, respectively, by means of the links 18 and 19, respectively, the end sections B may be pushed inwardly to close the table, carrying the slide members and leaves therewith until the outer edges of the leaves register or are positioned directly below the corresponding edges of the top board 1, as shown in Fig. 2. The end sections B, however, may be moved farther inward to take up the waste space and abut their edges 12' against the edges of the top board 1 to close the table. This continued inward movement of the end sections carries the cleats 16 and 17 inwardly beyond the guide cleats 35, as shown clearly in Fig. 1. This construction, therefore, permits an extension leaf for each end of the table substantially one-half of the width of the main top board 1—that is to say, as shown clearly in Figs. 1 and 2, the two leaves C, taken together, occupy substantially the same width of space that the main top board 1 occupies. In opening the table, it is evident that when the end sections B are pulled out and carry with them the cleats 16 or 17 until the ends of said cleats 16 or 17 register with the width of their particular leaf, as shown clearly in Fig. 5, and in order to prevent said cleats from moving any farther or beyond the leaves in an outward direction, I provide both the cleats 16 and 17 and the cleats 35 with stop members 38, as shown clearly in Figs. 4, 5, 6, 7, and 9, adapted to engage when the ends of the cleats 16 and 17 register with the edges of their respective leaves. As soon then as the top members engage the leaf, the leaves will be positively carried by the cleats 16 and 17 into position, as previously described. It may happen, however, on account of the friction between the several parts, that when the section B is pulled out in the operation of extending the table, the leaf C will move with the slides, 130

and when the operating links 18 arrive at the stops 20 the leaf and the cleats will be in the same relative position as they were when the table is collapsed. Further movement of the extension B outwardly to cause the lever links 18 to engage the stop would simply result in causing the cleats 16 or 17, as the case may be, to slide relatively to the leaf and the result is that the leaf would not be raised. In order to prevent this condition from arising, I provide stops or pawls 39 in the upper sides of the fixed slide members 15. These stops or pawls are pivoted at 40 in slots 41^a provided therefor, and their outer ends 42 are heavy so as to maintain the ends of the stops or pawls above the surface of the slides in an outward direction of movement of the leaf. On the underside of the leaves are transverse slots 43 to permit the movement of the leaves. At a point in the slots 43, which corresponds to the position in which the lever links 18 are about to engage the stops 20, there are small cross plates 44 which engage the stops 39 and hold the leaf until the cleats 16 or 17, as the case may be, are moved into position with their stop members 38 in engagement. A further movement of the end section B will cause the levers 18 to engage the stops 20 and elevate the leaf above the pawls 39, and the leaf will be in proper position relatively to the cleats 16 or 17 to position it in the plane of the top of the table. The weight ends 41 of these pawls 39 operate to hold the pawls in position during the outward or extended movement of the leaf, but will yield and allow the pawls 39 to be depressed into their slots 41^a when the leaf is moved inwardly. By means of this construction the maximum width of the leaves is obtained for a given size top board 1 of the table.

What we claim as our invention is:

1. In an extension table, the combination of a main and central section, a pair of fixed members, a pair of slide members slidably associated with said fixed members, an end table section supported by said slide members, a pair of cleats associated with said slide members, pivoted links connected to said slide members and to said cleats to form parallel motion connections between the cleats and slide members, means operable after the end section has moved away from said end section a given distance for actuating said links to raise the cleats, and an extension leaf slidably mounted on said cleats and adapted to be carried thereby into the plane of said main and central sections.
2. In an extension table, the combination of a main and central section, a pair of fixed members, a pair of slide members slidably associated with said fixed members, an end table section supported by said slide members, a pair of cleats associated with said

slide members, pivoted links connected to said slide members and to said cleats to form parallel motion connections between the cleats and slide members, pivoted stop members operable when the end section has been moved away from the main section for actuating said links to raise the cleats, an extension leaf slidably mounted on said cleats, and stop members limiting the sliding movement of said leaf.

3. In an extension table, the combination of a main and central section, a pair of fixed members, a pair of slide members slidably associated with said fixed members, an end table section supported by said slide members, a pair of cleats associated with said slide members, pivoted links connected to said slide members and to said cleats to form parallel motion connections between the cleats and slide members, pivoted stop members operable when the end section has been moved away from the main section for actuating said links to raise the cleats, an extension leaf slidably mounted on said cleats, stop members limiting the sliding movement of said leaf, and means operable by said end section when moved inwardly, positioning said pivoted stops for the next extension operation of said end section.

4. In a table of the class described, the combination of a main central section, an extensible end section, an extensible leaf normally contained beneath the main section and adapted to be interposed between the main and end section in the act of extending said end section and to be returned to its normal position in the act of returning said end section to non-extended position, means permitting a relative movement of the end section with respect to the leaf after said leaf has been restored to its normal position, and means operable in the act of extending said end section for restraining said leaf until said end section has been moved a given distance.

5. In a table of the class described, the combination of a pair of relatively separable table sections, an auxiliary leaf adapted to be positioned between said sections in the act of separating them, but normally positioned beneath said sections, means permitting a relative movement between said leaf and said sections in either direction of movement of said sections, and means operable during the separating movement of said sections for restraining the leaf after a certain degree of relative movement between the leaf and said sections has taken place.

Signed by us at Chicago, Illinois, this 4th day of May 1915.
